UNITED STATES PATENT OFFICE.

LOUIS K. VAUGHAN, OF WOODLAND, CALIFORNIA.

PEACH PITTER.

Application filed December 23, 1925. Serial No. 77,209.

This invention relates to improvements in devices for removing the stones or pits from peaches, and is especially adapted for use in connection with clingstone peaches. In 5 such peaches, as the name denotes, the pits tend to cling to the meat or pulp of the fruit, and while there are various more or less complicated machines for removing peach pits which are successful with freestone 10 peaches, none as far as I am aware, are suited for removing the pits of clingstone peaches.

The principal object of my invention is to provide a hand implement by means of 15 which an operator, after a certain amount of practice, can readily remove the pits from a whole box of peaches in from five to seven minutes, and without halving the fruit or spoiling the exterior appearance of the same 20 to any appreciable extent.

A further object of the invention is to produce a simple and inexpensive device and yet one which will be exceedingly effective for the purposes for which it is designed.

25 These objects I accomplish by means of such structure and relative arrangement of parts as will fully appear by a perusal of the following specification and claim.

In the drawings similar characters of reference indicate corresponding parts in the several views:

Fig. 1 is a sectional view of a peach, showing the pitter engaged with the pit thereof.

Fig. 2 is a perspective view of the peach 35 and pitter, showing the latter as being withdrawn from the peach with the pit.

Fig. 3 is a cross section of the jaw members of the pitter.

Referring now more particularly to the 40 characters of reference on the drawings, the numeral 1 denotes a pair of jaws, whose adjacent faces are somewhat concaved or grooved as shown at 2 in Fig. 3, and whose edges, both along the sides and around the 45 tips thereof are sharpened as at 3 for cutting purposes, the outer and inner surfaces of the jaws joining each other all along such edges at an acute angle, as shown. This shape and construction makes it easy to insert the jaws into the peach, and then turn the same when the jaws are thus embedded, for the purpose hereinafter shown.

The jaws, and the concave groove therein, 50 have a length greater than that of a peach pit, and at their inner ends are hinged together as at 4 in a suitable manner, such as

for instance as is employed in plier construction and the like.

A certain distance beyond the hinge, the 60 jaw members are bent at substantially right angles to form cooperating hand grips or handles 5. Spring means 6 disposed in any suitable location acts to hold the handles and jaws normally spread.

The operation of the device is as follows:

The pitter is held in one hand and a peach 70 in the other, the peach being held with its stem end facing the jaws, and with the plane of the split-line of the pit 8 parallel to the jaws, this position being determined by the 75 position of the grooved depression 7^a always evident on the outside of the peach.

The jaws are allowed to spread sufficient 80 to cause them to just clear the pit, and are then inserted the necessary distance into the peach about the pit as shown in Fig. 1, this distance being soon easily gauged after a little experience. The jaws are then brought together about the pit by pressing the grips 5 together, the pit seating in the concave groove of the jaws.

The peach and pitter are then turned relative to each other for a certain distance, or until the side cutting edges 3 of the jaws 85 have completely severed the fruit from the pit.

With the clamping pressure still maintained on the jaws to hold the pit firmly therebetween, the peach and pitter are pulled 90 apart, causing the pit to be withdrawn cleanly from the fruit, as shown in Fig. 2. Upon the jaws being allowed to spread apart, the pit may be discharged therefrom, and the tool is then ready to be used on another peach.

The hand grips are in the particular position shown, relative to the jaws, for the reason I have found this to be the most convenient and least tiring position for the hand 95 of the operator.

The pistol grip effect provides an admirable handle to hold the jaws in fixed position while impaling the peach and then these grips being at right angles to the flat plane of the jaws, provide a direct leverage 105 for the twisting operation to remove the pit. If the gripping handles project longitudinally of the jaws it is practically impossible for the operator to get a sufficient frictional grip on the same to permit easy twisting of 110 the pit. By having the right angle leverage however the operation is made an easy one.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A peach pitter comprising a pair of oppositely disposed substantially spoon shaped jaws adapted to be inserted into a peach to partially surround and grip the pit, hinge means connecting the jaws adjacent one end thereof, and handle grips on the jaws beyond the hinge and extending at substantially right angles to the flat plane of the jaws for clamping the jaws together on the pit and to form a leverage for twisting the jaws to cut the pit from the flesh of the peach.

In testimony whereof I affix my signature.

LOUIS K. VAUGHAN.
